UNITED STATES PATENT OFFICE

170,892

COMBINED HOLDER AND HANDLE FOR ELECTRIC SOLDERING IRONS AND THE LIKE

Alexander Schoenwald, Grove City, Pa., assignor
to P. Wall Mfg. Company, Grove City, Pa., a
corporation of Pennsylvania

Application March 19, 1953, Serial No. 24,102

Term of patent 14 years

(Cl. D26—1)

To all whom it may concern:

Be it known that I, Alexander Schoenwald, a citizen of the United States, residing at Grove City, Pa., have invented a new, original, and ornamental Design for a Combined Holder and Handle for Electric Soldering Irons and the like, of which the following is a specification, reference being had to the accompanying drawing, forming a part hereof.

Figure 1 is a side view of a combined holder and handle for electric soldering irons and the like embodying my design;

Fig. 2 is a front view thereof;

Fig. 3 is a bottom plan view thereof, and

Fig. 4 is a top plan view of Fig. 1.

I claim:

The ornamental design for a combined holder and handle for electric soldering irons and the like, as shown.

ALEXANDER SCHOENWALD.
